UNITED STATES PATENT OFFICE.

THEODORE G. WEYER, OF CHICAGO, ILLINOIS, ASSIGNOR, BY MESNE ASSIGNMENTS, TO
THE SENG COMPANY, A CORPORATION OF ILLINOIS.

BED-DAVENPORT.

1,269,766.

Specification of Letters Patent. Patented June 18, 1918.

Application filed August 4, 1915. Serial No. 43,614.

To all whom it may concern:

Be it known that I, THEODORE G. WEYER, a citizen of the United States, residing at 1334 N. Avers Ave., in the city of Chicago, in the county of Cook and State of Illinois, have invented certain new and useful Improvements in Bed-Davenports; and I do hereby declare the following to be a full, clear, and exact description of the invention, such as will enable others skilled in the art to which it appertains to make and use the same.

This invention relates to improvements in so-called bed davenports which when closed, constitute a davenport, sofa, arm chair or similar piece of furniture, and when opened provide a complete sleeping bed. The present invention relates more particularly to a structure of the character defined in which the seat and back of the davenport, lounge or chair are hinged together and are adapted to be moved outwardly from between the arms of said device, and become inverted to form a part of a mattress support or bed of standard length having a width equal to the distance between the arms of the article of furniture of which they constitute a part.

In the accompanying drawings illustrating the invention:

Figure —1— is a view in side elevation of a bed davenport constructed in accordance with my invention.

Fig. —2— is a front elevation of the same.

Fig. —3— is a vertical section of the same on the line 3—3 of Fig. 2.

Fig. —4— is a view similar to Fig. —3— showing the upper portion of the seat and the back extended to coact with the seat bottom to constitute a bed, and showing said upper seat portion and back in dotted lines in the primary position to which they are moved preparatory to being positioned as shown in full lines in said figure.

Figs. —5— and —6— are respectively a top plan view and a side elevation of a hinge employed for pivotally connecting the top and bottom seat portions together at their side rails.

Fig. —7— is a fragmentary top plan view of the bed davenport.

The device comprises a suitable frame preferably of wood consisting of four corner posts 1 and 2 for the front and back re-

spectively, which are connected together by 55 suitable side rails 3, rear cross-pieces 4 and front cross-pieces 5 all arranged below the plane occupied by the seat and are further connected together by means of the rear panels 6, the side arms 7 and side panels 60 preferably covering the said side rails 3. Secured to the said side rails or other convenient parts of the sofa-ends 3 are horizontally disposed supporting bars 8, formed preferably of angle iron which a suitable 65 spring fabric is stretched upon. Said supporting bars 8 are of less length than the depth of the lounge between the rails 4 and 5 and the space between the forward ends of the same and the forward end hinge members 70 70, preferably also formed of angle iron.

Pivots connected to the said pieces 10 of angle iron are similar hinge-members 11 which are secured to the side rails 12 75 of the underside of the seat frame. These side rails 12 may be connected together by means of cross-rails 13 and 14 respectively. Associated with the hinge members 11, and of which they practically form a continuation are angle iron strips 15, similar to the supporting bars 8 and which are secured to said side rails 12, each pair of hinge-members is connected by a plate 16 having two quadrant slots 17 disposed concentric 85 with pivot pins 18 mounted in said plates 16 and in the vertical flanges of said hinge-members 10 and 11. Each of the latter is provided with a projection 19 engaged in said slots 17 for limiting the pivotal movement of said hinge members relatively to said plate. Thus when the said hinge members 10 and 11 are disposed in the same horizontal plane shown in Fig. —6—, the plate 16 constitutes a rigid support for the hinge 95 member 11 upon the hinge member 10, it being obvious that the plate 16 is incapable of further pivotal movement.

When the seat is in position for use as such, as shown in Fig. —3—, the plates 16 become vertically disposed and the pins or projections 19 become disposed in the other ends of the slots 17 and in this position the upper edges of the vertical flanges of the hinge-members 10 and 11 rest upon each 100 other. This construction of hinge is particularly advantageous in that it produces a space to be maintained between the ends of 105

the side rails 12 and the opposed cross-pieces 5 of the sofa-frame in which a suitable covering of leather or similar material is adapted to be received and injury thereto 5 prevented.

The movable back frame of the structure comprises the side rails 20 connected together by means of cross-pieces 21 and 22, the latter preferably being of greater length 10 than the distance between said side rails 20 and being adapted to project over and rest upon the rear corner posts 2 and the upper end portions of the arms 7 of the frame when the back is closed, as shown in Fig. 15 —3—. It will be seen that in this instance the said cross-piece 22 is slightly angularly disposed relatively to the top or inner edges of the side rails 20 and that the lower or front edges of said rails 20 are also inclined 20 to the said top or rear edges thereof, the back being, when in closed position, inclined as shown in Fig. —3—. Secured to the lower edges of the side rails 20 are rails 23, formed of angle iron which project beyond the lower ends of said rails and also 25 beyond their intersection with the rear ends of the rails 15, at which points the rails 23 and 15 are pivotally secured by means of the pivot pins 24 passing through the vertical flanges thereof. The lateral flanges of 30 all of the rails 8, 15 and 23 respectively, rest upon the side rails of those elements to which they are secured, and as will be seen from Fig. —4— the lateral flange of the 35 extension portion of the angle iron 23 resting upon the lateral flange of the supporting bars 15 when the upper seat portion and back are disposed in the open position shown in Fig. —4—. In order that when in this 40 position the upper faces of the angle irons 15 and 23 may be flush over their combined length that portion of the angle iron 15 which is overlapped by the extension portions of the angle irons 23 are off-set as 45 shown at 25, a distance equal to the thickness of the horizontal flange of the rail 23. Secured to the side rails 20 contiguous to the cross-pieces 22 are pivoted legs 26 which are adapted to swing to vertical position as 50 the said back is turned to the position shown in full lines in Fig. —4—, to constitute supports for the outer or free end of said back, said arms 25 being adapted to swing preferably by gravity to the position shown in 55 full lines in Fig. —3— when the back is in closed position.

It will also be seen that the opposing end portions of the rails 12 and 20 are angularly cut away so that they will substantially 60 meet when the back and upper seat portions are disposed in closed position as shown in Fig. —3—. The back and seat frames will constitute suitable supports for base fabric and upholstery for providing 65 a soft cushioned seat and back for the daven-

port, lounge or chair when said parts are in closed position, said upholstery becoming inverted when said parts are in open position.

As will be apparent, the bed consists of three principal sections, namely, the stationary head-section, the middle-section, and the foot-section, and in addition, the narrow spacing-section formed by the coupling-plates 16 and the hinge-members 10 and 11, to all intents and purposes being but extensions or continuations of the rails 8 and 15 respectively. Unlike other beds of this class, cross-rails for connecting the outer ends of the side-rails 8 and 23, are not required though they may be used. In the present instance, however, the woven-wire fabric 9, forming the mattress-support, is merely stretched between the side-rails of the several sections and the hinge-members and is therefore capable of folding or flexing with the bed at the various joints of the latter.

The mattress 9 is suitably tied to the wire fabric or frame-work at proper points so that it will fold up as shown in Fig. —3— 90 when the parts are in closed position, and will not become displaced during the pivotal movement of said parts from closed to open position, or open to closed position, respectively.

It will be seen that weight of the seat and back portions when in open or bed position will tend to break down the pivotal connection between the side rails thereof, and that this will be resisted by the bearing 100 of the extension portions of the side rails 23 which overlap the side-rails 15 so that when in open or bed position the side rails 15 and 23 will constitute a very rigid support for the weight of the occupant of the 105 bed.

By reference to Fig. 3, wherein the device is illustrated in closed or sofa-form, it will be seen that the spacing-plates 16 serve to permit the middle bed-section to fold over 110 and upon the stationary head-section formed by the bars or rails 8, and to space these parts a sufficient distance apart to accommodate the folded mattress and other bedding employed. It will further be seen that when the parts are thus positioned, the extensions of the side rails 23 of the foot-section—that is, those portions extending beyond their points of pivot 24 with the rails 15 of the middle-section—rest upon the rails 8 of the 115 head-section and thus support the weight of the back as well as that of the rear edge of the seat and also combine with the spacing-plates 16, with which they approximately coincide in length, to maintain the head and 120 middle-sections apart to receive the mattress and other bedding. The mattress, it will be observed, is thus divided or folded about in thirds—the two rear thirds or those above the foot and middle-sections being folded 125 130

compactly one upon the other and lying between the head and middle-sections and the outer third becoming positioned in rear of the back and hence the foot-section.

5 My said device is extremely simple in construction and relatively cheap, besides being very easily operated and requiring no manipulation of locking devices such as are employed in substantially all of the bed 10 davenports now on the market. The device presents a very neat appearance when in closed position, and may be freely ornamented as to all of the exposed wood-work and any desired kind of upholstery provided 15 therein to provide the greatest of comfort for the article as an article of furniture, while at the same time the structural characteristics thereof when converted into a bed are such as to provide the greatest degree 20 of comfort reasonably to be expected from a device of this dual character.

I claim as my invention:

1. In a davenport bed, the combination, with a main-frame comprising opposite ends, 25 of a head-section fixedly mounted in the main-frame between the ends, a middle-section, a narrow spacing and hinging means loosely connected at opposite ends to the adjacent ends of the head and middle-sections, whereby the said middle-section is 30 adapted to fold inwardly and over the head-section between the ends and the fronts of the two sections spaced apart by the spacing-section, a foot-section having its side rails 35 pivoted to the ends of those of the middle-section and extended beyond their pivots a distance approximately agreeing with the length of the spacing and hinging means, whereby when the bed is folded the foot-section 40 is positioned angularly with relation to the middle-section, the side bars of the foot-section extend below the middle-section and rest upon the head-section and the middle and head-sections are maintained in substantially parallel relation and combine to 45 form an intermediate bedding-space, a seat

carried by the middle-section, and a back carried by the foot-section.

2. In a davenport bed, the combination, with the main-frame comprising opposite 50 ends, of opposite horizontal supporting-rails secured to the inner surfaces of the ends of the main-frame and terminating short of the front of the same, hinge-members also connected to said ends and forming continuations 55 of the supporting-rails and terminating at the front of the main-frame, a superimposed seat-frame, side-rails connected to the opposite ends thereof and terminating at their front ends coincident with said supporting-rails of the main-frame and short of the front of the seat-frame, companion 60 hinge-members secured to said seat-frame and terminating at the front thereof and forming continuations of the side-rails, a 65 spacing-plate pivotally connected to each pair of hinge-members and having but a limited pivotal movement in each direction and serving to space the hinge-members apart, a sofa-back frame abutting the rear of the 70 sofa-seat frame, legs connected to the back-frame and adapted to support the same when inverted in front of the main-frame, side-rails secured to the opposite ends of the back-frame and extending below the same 75 and resting upon the supporting-rails of the main-frame, pivotal connections between the said rails and those of the seat-frame at points above the lower ends of the former, whereby a bedding-space is formed between 80 the supporting-rails and side-rails of the seat-frame, and a woven-wire mattress-support connected to each pair of said rails and hinge-members.

In testimony whereof I have signed my 85 name in presence of two subscribing witnesses.

THEODORE G. WEYER.
